UNITED STATES PATENT OFFICE.

PAUL RAYMOND SIMMONS, OF MARION, INDIANA.

DISH-CUTTING MACHINE.

1,044,931.

Specification of Letters Patent.

Patented Nov. 19, 1912.

Application filed October 20, 1911. Serial No. 655,777.

To all whom it may concern:

Be it known that I, PAUL RAYMOND SIMMONS, a citizen of the United States, and a resident of Marion, in the county of Grant 5 and State of Indiana, have invented a new and Improved Dish-Cutting Machine, of which the following is a full, clear, and exact description.

My invention relates to a dish-cutting machine, and relates more particularly to that class of machines in which a roll of paper is cut into shapes ready to be pressed into the form of dishes or pie plates.

An object of my invention is to provide a machine which will readily, accurately and economically cut a roll of paper into the required shape or size, and in which the cutting elements may be changed or modified to cut different sized dishes or patterns.

20 I attain the above outlined object by mounting upon one of two contacting rollers, changeable blocks carrying different configuration of knives, and by regulating the pressure of the other roller against the 25 knife-carrying roller, so as to cut a roll of paper passing between the rollers into the configuration outlined by the knives.

With the above and other objects in view, as will more fully hereinafter appear, the 30 present invention consists in certain novel details of construction and arrangement of parts hereinafter fully described, illustrated in the accompanying drawings, and more particularly pointed out in the appended 35 claims.

Reference is to be had to the accompanying drawings, forming a part of this specification, in which similar characters of reference indicate corresponding parts in all 40 the figures, and in which—

Figure 1 is a front elevation of a preferred embodiment of my machine, certain parts being broken away to disclose details; Fig. 2 is a transverse sectional view taken 45 on the line 2—2 of Fig. 1; Fig. 3 is a perspective view showing one of the knife-blocks detached from the roller, and Fig. 4 is a part of a roll of paper showing the patterns cut therein.

50 Spaced apart upon a base 4 and fastened to said base by bolts 5, is a pair of uprights 6 of any suitable construction, each of which uprights has a bearing 7 therein, carrying a shaft 8; rigidly upon said shaft, intermediate the uprights 6, is a knife-carrying drum 9. One end of the shaft 8 terminates

outside of the adjacent upright in a power wheel 10, the opposite end of said shaft outside of its adjacent end having rigidly mounted thereon a gear wheel 11. This gear wheel is in permanent mesh with a similarly constructed gear wheel 12 rigidly mounted upon one end of a shaft 13, which shaft extends above and parallel to the shaft 8, and rigidly mounted upon the shaft 13 and 60 coacting with the drum 9 is a roller 14. The shaft 13 is loosely mounted in a pair of journal boxes 15, which journal boxes are square in cross section, as shown more particularly in Fig. 2, and are capable of vertical movement in slideways 16, and enlarged portions 17 of the uprights 6, and above each of the bearings 7. The journal boxes 15 are supported by coil springs 18 disposed in pockets 19 above the bearings 7, and the 65 roller 14 is adjustably pressed into engagement with the drum 9 by means of a bearing bolt 20 mounted in the top of each upright 6, and bearing upon the journal boxes 15. By this construction it is seen that the tension between the rollers 14 and 9 may be 70 regulated.

As shown more particularly in Fig. 2, the roller 9 has a series of pockets 21 spaced about its periphery, each longitudinal side 85 of each of said pockets being in a plane to form pyramidal pockets passing through the axis of rotation of the drum. Adapted to be disposed in the several pockets 21, are knife blocks 22, said knife blocks having positioned thereon, cutting knives 23, and extending through said blocks are apertures 24 by means of which the blocks may be 90 removably fastened to the drum 9. These knives 23 may be of any desired configuration and as shown in the drawings, are fragments of circles, so that several of the knife-carrying blocks suitably arranged will cut a roll of paper 25 passing between the rollers into the shapes shown in Fig. 4. Further, 100 several of the blocks may carry straight cutting knives 26, whereby cuts 27 may be made from the edge 28 of the roll of paper to the edge of a pattern 29. The edges of adjacent patterns are tangent to each 105 other, whereby the greatest number of plates may be cut from the minimum amount of paper.

In order to guide the roll of paper, a pair of fingers 30 are disposed on opposite sides 110 of the roll, said fingers being rigidly mounted upon a rod 31 journaled at opposite ends

in brackets 32, which brackets are mounted upon the front of the uprights 6.

Having thus described my invention, I claim as new and desire to secure by Letters Patent:

1. In a paper-cutting machine, a roller, a series of removable blocks carried by said roller, and rigid knives mounted on said blocks, said knives being independent of each other and arranged to cut a circular pattern in the paper, certain of said blocks carrying knives common to two circular patterns, whereby the knives common to two circles may be carried by one block.
- 15 2. In a paper-dish-cutting machine, means for cutting a roll of paper into designs, said

means comprising a knife-carrying roller having a series of spaced-apart frusto-pyramidal pockets disposed about its periphery, a knife block disposed in and fitting each of said pockets, means for removably fastening said blocks in position, and a knife carried by each block, the knives of adjacent blocks coacting to cut a pattern.

In testimony whereof I have signed my name to this specification in the presence of two subscribing witnesses.

PAUL RAYMOND SIMMONS.

Witnesses:

JAMES H. McCONNELL,
CHARLES J. DARTER.
